(57) CLAIM

The ornamental design for a ball cover, as shown and described.

DESCRIPTION

FIG. 1 is a front view of the ball cover;

FIG. 2 is a top view thereof; and,

FIG. 3 is a front perspective view thereof.

The broken lines illustrate portions of the ball cover which form no part of the claimed design.

1 Claim, 3 Drawing Sheets

FIG. 3
